CLAIM

The ornamental design for a novelty ice making mold, as shown and described.

DESCRIPTION

FIG. 1 is a perspective view of the novelty ice making mold showing my new design in the partially open configuration;

FIG. 2 is a top plan view thereof;

FIG. 3 is a bottom plan view thereof;

FIG. 4 is a side elevational view thereof, the side opposite being a mirror image of the side shown in FIG. 4;

FIG. 5 is a right end elevational view thereof;

FIG. 6 is a left end elevational view thereof; and,

FIG. 7 is a perspective view thereof in the open condition and showing the inside surface.

FIG. 2.

FIG. 4.

FIG. 3.

FIG. 5.

FIG. 6.

FIG. 7.
